UNITED STATES PATENT OFFICE.

ELLSWORTH A. HAWTHORNE, OF BRIDGEPORT, CONNECTICUT.

MOUNTING FOR LAMPS AND LAMP-SUPPLY CONTAINERS.

1,201,293.

Specification of Letters Patent.

Patented Oct. 17, 1916.

Application filed April 27, 1914. Serial No. 834,629.

To all whom it may concern:
Be it known that I, ELLSWORTH A. HAWTHORNE, a citizen of the United States, and a resident of Bridgeport, county of Fairfield, and State of Connecticut, have invented an Improvement in Mountings for Lamps and Lamp-Supply Containers, of which the following description, in connection with the accompanying drawings, is a specification, like characters on the drawings representing like parts.

This invention relates to mountings for lamps and lamp containers, such as batteries, gas tanks, generators and the like, and will be best understood by reference to the following specification, when taken in connection with the accompanying drawings of one illustrative embodiment thereof, while its scope will be more particularly pointed out in the appended claims.

In the drawings: Figure 1 is a plan of a lamp supply container and mounting therefor embodying my invention, as mounted upon a steering structure, the latter being partially shown; Fig. 2 is a side elevation of the same; Fig. 3 is a detail sectional view, on an enlarged scale, on line 3—3 of Fig. 2, illustrating the attachment of one of the attaching strips of the mounting; Fig. 4 is a detail sectional view, on an enlarged scale, on line 4—4 of Fig. 2, illustrating the pivotal attachment of the mounting to the clamps upon the steering structure; Fig. 5 is a detailed sectional view on a larger scale taken on the line 5—5 of Fig. 2; Fig. 6 is a detail sectional view on an enlarged scale, on line 6—6 of Fig. 2, illustrating in longitudinal section the shock-absorbing device; and Fig. 7 is a side elevation of the mounting, having thereon a lamp and a lamp supply container, the latter being of a different type from that shown in Figs. 1 and 2.

Referring to the drawings, and to the embodiment of my invention which I have selected for illustration, I have there shown a mounting for lamps and lamp supply containers, which may serve other useful purposes, but which is particularly intended to be supported upon a motor cycle steering structure, a portion of the latter being conventionally represented at 10. This steering structure may be of any other appropriate construction, but herein comprises a pair of forked sides 11, having struts, or brace members, 12.

The mounting itself herein comprises two side members 13—13, consisting of plates disposed in substantially vertical planes, and herein united by a plate 14, the latter being preferably disposed in a substantially horizontal plane. The side plates may be secured to the top plate in any other appropriate manner, but herein each is provided with an inwardly projecting flange 15, having slots 16 and 17, to receive bolts 18 and 19, by means of which the top plate may be secured in adjustable relation with the side plates. The top plate 14 may be imperforate, if desired, but as herein shown is provided with a perforation 20, which may receive a lamp supply container of any appropriate character, such for example as a battery housing 21, shown in Fig. 7. In case it should be desired to place a gas tank upon the mounting, each of the plates 13 is provided with an opening 22, to receive a gas tank 23, the latter being sustained by the plates, and extending a short distance therebeyond at each end (see Fig. 1).

Any appropriate means may be provided for securing the gas tank, but herein the latter is partially encircled by a pair of straps 24, each secured to one of the flanges 15. Any suitable mode of attachment may be utilized, but herein each strap has a terminal portion 25, provided with oppositely disposed notches 26, constituting a species of key inserted in an opening 27 in the flange, said opening having oppositely disposed notches 28, whereby the strap may be introduced into the opening and turned, so as to interlock with the flange in the normal position of the strap. The other end of the latter may be secured to the flange in any other appropriate manner, but herein the bolt 18, already referred to, passes through a lug or ear 29, formed on such terminal portion.

In practice, the straps will be so proportioned that the lugs 29 will be slightly separated from the flanges 15, so that the straps will exert a clamping action upon the gas tank, and draw the latter against the upper margin of the opening 22, thereby firmly holding the tank in place. When the gas tank is to be removed, this may be accomplished by simply loosening the bolts 18 very slightly, after which the tank may be withdrawn endwise from its place.

The mounting may support the lamp in any other appropriate manner, but herein a

lamp 30 is provided in a well-known manner at both sides with lugs, one of which is shown at 31, and each of these lugs is herein supported upon a post 32, the latter being 5 forked at 33 to embrace an ear 34 on the plate 13, there being provided a bolt 35, by means of which the two sides of the post may be drawn together, thereby to clamp the ear between them. By this means, the 10 lamp is so mounted as to be capable of adjustment about a horizontal axis, and may be rigidly secured in the desired position of adjustment.

As a means for cushioning the lamp and 15 lamp supply container to prevent possible injury thereto by reason of road shocks, the mounting is movably mounted upon its support to move in a vertical plane, and there is provided means yieldingly resisting downward movement, thereby to absorb the 20 shocks due to inequalities of the road. This may be accomplished in other ways, but herein the mounting is pivoted upon its support to swing in a vertical plane, there being provided for this purpose a pair of clamps 36, each comprising a pair of plates 37, interlocked with each other at 38, and clamped about the forked side 11 by means 25 of a clamping bolt 39, which passes through both plates and through an ear 40 formed on the plate 13, and interposed between the clamping plates 37. As a means for preventing the clamping plates 37 from being clamped against the ear 40 by the bolt 39, 30 the latter is herein encircled by a bushing or sleeve 41, whose length is slightly greater than the thickness of the ear 40 (see Fig. 4). By this means, the mounting is permitted to turn freely upon the bushings 41 as pivots. 35 Any other appropriate means may be employed for cushioning the lamp mountings, but herein each plate 13 is provided with a slot 42, in which is disposed a spring 43, so arranged as to be compressed by the downward movement of the mounting about its 40 pivotal axis. This spring herein encircles a pair of tongues 44, the latter being formed on clamping plates 45 embracing the strut 12, and clamped about the latter by means 45 of a clamping bolt 46 and a second clamping bolt 47, the latter passing through the slot 42, and being encircled by a bushing or sleeve 48, by means of which the clamping plates are prevented from clamping the 50 plate 13 therebetween. The sleeve 48, moreover, constitutes a stop for limiting the upward movement of the mounting about its axis (see Figs. 2 and 6). If desired, the spring 43 might abut, at one end directly 55 against the end of the slot 42, and at its other end against shoulders 49 formed by reduced portions, or tongues, 44, but I prefer to employ two abutments 50, which are alike, and one of which is shown in Fig. 5 60 as being provided with a pair of diametri-

cally opposite notches 51 to receive the plate 13, and a pair of perforations 52 to receive the tongues or reduced portions 44. In assembling the device, these plates are first slipped into place, and the spring introduced between them, after which the tongues are introduced through the openings in the plate, and through the interior of the spring, thus holding the latter in place, yet permitting a perfectly free action of the same.

75

It will now be evident that, as the motor cycle or other vehicle is passing over the road, the springs will absorb the shocks due to any road inequalities, which would otherwise be apt to cause injury to the mounting, 20 to the lamp, or to the lamp supply. By this means, the lives of these parts may be greatly prolonged.

While I have herein shown and described one specific embodiment of my invention for 85 illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention 90 may be made, without departing from the 95 principles thereof.

Having thus described my invention, what I claim and desire by Letters Patent to procure is:—

1. The combination with a suitable support, of a lamp-mounting pivoted at its rear side adjacent the upper end thereof on said support to swing in a vertical plane, and means yieldingly to resist downward movement of said lamp-mounting about its pivotal axis against which said rear side of the lamp mounting bears adjacent its lower end.

2. The combination with a suitable support, of a lamp-mounting pivoted at its rear side adjacent the upper end thereof on said support to swing in a vertical plane, a member secured to said support, and a spring interposed between said member and said lamp-mounting and bearing against the latter adjacent the lower end of said rear side, 110 said spring tending to resist downward movement of said lamp-mounting about its pivotal axis.

3. The combination with a suitable support, of a lamp-mounting pivoted to said support to swing in a vertical plane, said lamp-mounting being provided with a slot, a member secured to said support, abutments on said lamp mounting and on said member and a spring disposed in said slot 125 and having its ends respectively bearing against the abutments on said member and said lamp-mounting.

4. The combination with a suitable support, of a lamp-mounting pivoted to said 130

- support to swing in a vertical plane, said lamp-mounting being provided with a slot, a member secured to said support, abutments on said lamp mounting and on said member 5 and a spring disposed in said slot and having its ends respectively bearing against the abutments on said member and said lamp-mounting, said member extending through said spring to hold the latter in place.
- 10 5. The combination with a suitable support, of a lamp-mounting pivoted on said support to swing in a vertical plane, said lamp-mounting being provided with a slot, a pair of members secured to said support, 15 means extending through said slot and connecting said members, and a spring tending to resist movement of said means in said slot.
- 20 6. The combination with a suitable support, of a lamp-mounting pivoted on said support to swing in a vertical plane, said lamp-mounting being provided with a slot, a pair of members secured to said support, means extending through said slot and connecting said members, said members having 25 reduced portions forming shoulders, and a spring interposed between said shoulders and the opposite end of said slot.
7. The combination with a suitable support, of a lamp-mounting pivoted on said support to swing in a vertical plane, said lamp-mounting being provided with a slot, a pair of members secured to said support, means extending through said slot and connecting said members, said members having 30 reduced portions forming shoulders, a plate forming an abutment disposed against said shoulders, another plate forming an abutment disposed against the opposite end of 35 said slot, said reduced portions passing through said plates, and a spring encircling 40 said reduced portions and interposed between said plates.
8. The combination with a suitable support, of a lamp-mounting pivoted on said support to swing in a vertical plane, said lamp-mounting being provided with a slot, a pair of members secured to said support, means extending through said slot and connecting said members, said members having 45 reduced portions forming shoulders, a plate forming an abutment disposed against said shoulders, another plate forming an abutment disposed against the opposite end of 50 said slot, said plates being each provided with a pair of oppositely disposed marginal notches to receive portions of said lamp-mounting, said reduced portions passing through said plates, and a spring encircling 55 said reduced portions and interposed between said plates.
- 60 9. The combination with a suitable support

port, of a lamp-mounting pivoted on said support to swing in a vertical plane, said lamp-mounting being provided with a slot, 65 a pair of members secured to said support, a spring disposed in said slot and encircling said members and having abutment against the lamp-mounting and said members.

70 10. The combination with a suitable support, of a lamp-mounting, pivoted on said support to swing in a vertical plane, said lamp-mounting being provided with a slot, a pair of members secured to said support 75 and lying adjacent opposite sides of said slot, a spring disposed in said slot and encircling said members and abutting against the lamp-mounting and said members.

11. A lamp-mounting comprising a pair 80 of plates disposed in substantially vertical planes, a plate disposed in a substantially horizontal plane and uniting the first mentioned plates, the vertical plates being apertured and a lamp-supply container secured 85 in said apertures and means to secure a lamp thereto.

12. A lamp mounting comprising a substantially horizontally disposed plate and means for securing a lamp in superposed relation thereto, a vertically disposed plate secured beneath said first plate and means to secure the latter pivotally to a support at the upper part of one edge and yielding means to resist downward movement on the 90 pivot acting on the lower part of that edge.

13. A mounting for a lamp-supply container, comprising, in combination, a pair of supporting members provided with openings for the lamp-supply container, and a 100 pair of straps for securing said container in place in said openings.

14. A mounting for a lamp-supply container, comprising, in combination, a pair of supporting members provided with openings for the lamp-supply container, a pair 105 of straps, and means to secure said straps to said supporting members thereby to hold the container in place in said openings.

15. A mounting for a lamp-supply container, comprising, in combination, supporting means provided with an opening or openings for the lamp-supply container, and means including a strap for securing said container in place in said opening or openings.

In testimony whereof, I have signed my name to this specification, in the presence of the subscribing witnesses.
